UNITED STATES PATENT OFFICE.

HENRY B. BEACH AND HENRY J. KAYSER, OF MERIDEN, CONNECTICUT,
ASSIGNORS TO INTERNATIONAL SILVER CO., OF MERIDEN, CONNECTI-
CUT, A CORPORATION OF CONNECTICUT.

DESIGN FOR A CANDELABRUM.

No. 38,637.

Specification for Design.

Patented June 25, 1907.

Application filed May 7, 1907. Serial No. 372,443. Term of patent 7 years.

To all whom it may concern:

Be it known that we, HENRY B. BEACH and HENRY J. KAYSER, both citizens of the United States, residing at Meriden, in the county of New Haven and State of Connecticut, have invented a new, original, and ornamental Design for a Candelabrum, of which the following is a specification, reference being had to the accompanying drawing, forming part hereof.

In the drawing, Figure 1 is a side elevation

of the candelabrum showing our design, Fig. 2 is a top plan view, and Fig. 3 is an elevation of the base.

We claim:

The ornamental design for candelabrum, as shown.

HENRY B. BEACH.
HENRY J. KAYSER.
